UTILITY HANDBAG

Harry Paris, Los Angeles, Calif.

Application August 9, 1954, Serial No. 31,782

Term of patent 3½ years

(Cl. D87—3)

Fig. 1.

Fig. 2.

To all whom it may concern:

Be it known that I, Harry Paris, a citizen of the United States of America, residing in Los Angeles, county of Los Angeles, and State of California, have invented a new, original, and ornamental Design for a Utility Handbag, of which the following is a specification, reference being had to the accompanying drawing, forming part thereof.

Fig. 1 is a front perspective view of a utility handbag, showing my new design.

Fig. 2 is a rear perspective view of said bag.

The dominant features of the design are shown in full lines in the drawing.

I claim:

The ornamental design for a utility handbag, substantially as shown and described.
